Primary Examiner — Susan E Krakower*Assistant Examiner* — Lisa A Grabenstetter(74) Attorney, Agent, or Firm — Dunlap Bennett & Lugwig PLLC; Brendan Squire(57) CLAIM

The ornamental design for a cell phone case, as shown and described.

DESCRIPTION

FIG. 1 is a front perspective view of the cell phone case showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings illustrate portions of the cell phone case that form no part of the claimed design. The dash-dot-dash line indicates the boundary that forms no part of the claimed design.
